DISPLACEMENT VALVE GAS LIFT

Mark P. Burke, Long Beach, Calif.

Application June 8, 1939, Serial No. 278,110

9 Claims. (Cl. 103—232)

This invention relates to apparatus for pumping liquids from wells and is particularly concerned with a displacement valve gas lift. Inventions of this general type have been shown in my Patent No. 1,803,837 entitled "Gas lift means," issued to me March 5, 1931, and my co-pending applications for U. S. Letters Patent entitled "Fluid lift" and "Fluid operated means," filed April 21, 1938, and bearing Serial Numbers 203,451 and 203,452, now Patents 2,259,949, October 21, 1941, and 2,251,323, August 5, 1941, respectively.

At the present time it is necessary that oil well pumping equipment be designed to meet all prevailing conditions, such as those caused by differences in fluid yield and liquid head and other conditions arising because of proration restrictions to control the output of wells in a given field and to regulate production generally. In my Patent No. 1,803,837, previously mentioned, I have shown a structure for use in small wells where there is not a sufficient liquid head standing within the well to prevent gas from breaking through the liquid column and causing it to get out of control. In that particular construction the valve shown is of the bellows type, which opens when a surface intermitter opens the surface control valve allowing the fluid under pressure to force the slug of liquid from the well and to close when the surface intermitter stops the flow of fluid into the well, allowing gas to escape through the flow tube until the gas pressure is less than the spring pressure of the valve. The fluid control valve, as shown in that patent, is placed above a liquid accumulating chamber, and when the valve is opened the fluid pressure is exerted downwardly on the liquid in the chamber and the liquid is then forced up into a macaroni tube and out of the well. The accumulating chamber is shown in that patent as being a multiplying chamber since the volume of liquid which has accumulated in this chamber is forced upwardly into a pipe of smaller cross-sectional area, giving the liquid an additional fluid head. In that particular case a surface control valve with an intermitter is shown as providing a control for the fluid which supplies the lifting force in the well.

As previously stated, the device of the patent has been designed for use in wells having a relatively low hydrostatic fluid head and would not operate with the greatest of efficiency in wells which have a relatively high liquid level and hydrostatic head and have a yield of cognant fluid of large potential.

It is the principal object of the present invention, therefore, to provide a fluid lift structure which will operate efficiently in wells within which a high lift liquid level and large potentials exist, and which will respond to the standard pressure of a lifting fluid available for the purpose.

The present invention contemplates the provision of a surface intermitter and a control valve which governs the pressure flow of a lifting fluid conducted to the pumping apparatus in the well. A liquid control valve is also provided to permit only a predetermined amount of liquid to enter the tube, and a pressure fluid control valve is disposed in the lower end of the flow tubing above the liquid control valve, and it cooperates therewith in a maner to insure that when the fluid control valve is opened the pressure of the pressure fluid is exerted upwardly against the accumulated column of liquid and forces this slug of liquid out of the well. The structure also contemplates the provision of an enclosed chamber within which the pressure fluid control valve and the liquid control valve are encased, said chamber being in communication with the space around the valves in the tubing, thus permitting any leakage of fluid to escape through an exhaust valve during the cycle of pressure change which occurs when the liquid is being forced from the well and after the slug has been discharged, the valves being so arranged as to prevent them from becoming fluid locked since the fluid pressure within the chamber is free to equalize with the pressure in the space around the valves after the slug has been forced from the well and the pressure is almost atmospheric pressure. With the fluid lifting mechanism here shown it is proposed to use an intermitter and surface control valve such as disclosed in my co-pending application filed by me in the U. S. Patent Office on April 21, 1938, Serial No. 203,452, and which application is entitled "Fluid operated means," now Patent 2,251,323, August 5, 1941.

45 The invention is illustrated by way of example in the accompanying drawings, in which:

Figure 1 is a view in section and elevation with parts broken away showing the application of the present invention to a well.

50 Fig. 2 is an enlarged view in longitudinal section through the fluid control valve structure, as seen on the line 2—2 of Fig. 1.

Fig. 3 is an enlarged view in central longitudinal section through the automatic liquid control valve, as seen on the line 3—3 of Fig. 1.

Fig. 4 is a view in transverse section through the fluid control valve, as seen on the line 4—4 of Fig. 2, and indicates the formation and arrangement of the gas inlet and exhaust ports.

Fig. 5 is a view in transverse section through the automatic liquid control valve, as seen on the line 5—5 of Fig. 3, and discloses the arrangements of the parts and the position of the liquid ports.

Referring more particularly to the drawings, 10 indicates a fluid delivery pipe through which gas under pressure is delivered to the top of the well. A cut-off valve structure 11 is interposed in this gas line and is controlled by surface intermitter 12, the details of which are more clearly disclosed in my co-pending application, as aforementioned. The intermitter acts to establish a flow of gas to the well in predetermined volume and pressure and for a predetermined period, after which the flow of gas is interrupted for a predetermined period during which a liquid column will accumulate within the flow pipe, as will be hereinafter described. The pressure fluid, after passing through the valve 11, travels through pipe 13 to the casing 14 with 15 which the pipe is connected. This casing extends downwardly into the well and is shown as being fitted at its lower end with a perforated well screen section 15. A suitable casinghead 16 is fastened at the upper end of the casing 14 and through which a flow tube 17 extends. The flow tube 17 extends downwardly to a point adjacent the lower end of the well where its open end 18 is free to receive cognate fluid from the formation surrounding the well screen 15. Mounted adjacent the lower end of the flow tube 17 is a standing valve 19 provided with a valve ball 19'.

At a suitable point in the length of the casing a packer 20 is mounted upon the tubing and 40 forms a fluid seal between the well casing and the tubing so that a well fluid compartment 21 will occur beneath the packer and prevents the well fluid from passing upwardly only through the flow tube 17.

Mounted within the flow tube 17 and above the standing valve 19 is a liquid control valve unit 22. This unit is shown more particularly in Fig. 3 of the drawings. The liquid control valve unit includes an equalizing valve housing 23 suitably secured within the flow tube 17. This valve housing is formed with a valve chamber 24 having an upper wall 25 and a lower wall 26. The upper wall is formed with a central downwardly presented valve opening and seat 27, and the lower wall is formed with a central downwardly presented valve opening and seat 28. An equalizer valve spool 29 extends through the valve opening 28 and carries an upper valve element 30 adapted to seat against the valve seat 27 and a lower valve element 31 adapted to seat against the valve seat 28. These valve elements are of the poppet type. The valve spool 29 is slidably mounted upon a valve stem 32, which stem is threaded into the lower end of an exhaust tube 33. Formed centrally through the stem 32 is an equalizer passage 34. Interposed between the lower end of the exhaust tube 33 and the upper face of valve 30 is a valve spring 35. Interposed between the lower face of the valve element 31 and a nut 36 is a valve spring 37. By this means it will be seen that the valve spool 29 will be supported yieldably upon the valve stem 32 and will seat irrespective of minor variations and movement of the valve stem and the exhaust tube,

The lower valve element 31 is mounted to reciprocate within a downwardly extending cylindrical extension 38, which extension is closed at its lower end by a threaded plug 39. The valve element 31 has a sliding fit within the extension 38 and the fluid space below the valve is in communication with the equalizing passageway 34 which leads upwardly through the exhaust tube 33 and is closed at its lower end by an exhaust valve 40. The exhaust valve 40 includes a threaded valve seat 41 having a port 42 therethrough, which is closed by a valve ball 43. The valve ball 43 is yieldably held upwardly to its seated position by a spring 44. Thus, fluid may pass downwardly through the valve port 42 but cannot pass upwardly.

At a point in the length of the exhaust tube 33 are exhaust ports 45 which extend through the wall thereof. With this arrangement fluid pressure on opposite sides of the exhaust valve structure 23 will be equalized after the slug has been forced from the well. The upper end wall 25 of the equalizer valve housing 23 carries a guide bearing 46 through which the exhaust tube 33 may reciprocate.

The upper end of the exhaust tube 33 is threaded into the lower end of a tubular valve plunger 47. This plunger is cylindrical and has a central chamber 48 extending longitudinally therethrough. At a point intermediate the ends of the plunger an enlarged outside collar 49 occurs. This collar has a lower tapered valve shoulder 50 and an upper tapered valve shoulder 51. The portion of the plunger below the shoulder 50 extends into a lower valve sleeve 52. The sleeve has a central cylindrical bore with relation to which the valve plunger has a free fit. A tapered valve seat 53 is formed at the upper end of this bore and against which the valve shoulder 50 rests. A tapered valve seat 54 is formed at the lower end of this bore and receives a tapered valve face 54' formed on the end of the plunger 47. The exhaust tube 33 extends through a central opening in the lower valve sleeve 52. Thus, it will be seen that the exhaust tube 33 and the valve spool 29 are carried by the valve plunger 47 and moved therewith.

The lower valve sleeve 52 is mounted within a liquid control valve housing 55. This valve housing has an enlarged cylindrical lower portion which fits within the flow tube 17 and is secured in position by any suitable means, such for example as welding, as indicated at 56. Formed as a continuation of the lower enlarged portion of the housing is an upwardly extending guide tube 57. The lower portion of the housing and the guide tube are formed with a central bore 58 within which the lower valve sleeve 52 fits. At the upper end of the bore a shoulder 59 occurs and receives an upper valve seat 60. The upper valve seat 60 is suitably spaced from the lower valve sleeve 52 by a spacing bushing 61. The valve seat 60 has a central opening therethrough to receive the upper extending end of the plunger 47 and is formed with a tapered valve face 62 against which the tapered shoulder 51 on the plunger 47 may seat. It will be seen by an examination of Fig. 3 of the drawings that the space between the shoulders 50 and 51 on the plunger is less than the space between the faces 53 and 62 of the lower and upper valve seats 52 and 60, respectively. This spacing is represented by the height of the spacing bushing 61.

The guide tube 57 extends upwardly a distance 75 above the upper end of the plunger 47 and pro-

vides a chamber within which a plunger spring 63 is mounted. This spring rests against the upper face of the plunger 47 and is held in position by an adjusting nut 64 which has a fluid passageway 65 therethrough. The upper end of the guide tube 57 is closed by a plug 66.

The lower end of the liquid control valve housing 55 carries a tubular lock nut 67 which is threaded into the bore 58 and rests against the lower face of the valve sleeve 52.

Attention is directed to the fact that the bore through the valve seat 54' of the lower valve sleeve 52 is materially larger than the diameter of the exhaust tube 33, thus providing a fluid passageway 68.

It is also to be pointed out that the guide bearings 46 are supported by arms permitting a free flow of fluid through the valve openings 27 and 28 of the equalizer valve structure, and that in addition liquid ports 69 are formed through the wall 26 of the equalizer valve housing. This establishes direct communication between the equalizer valve chamber 24 and the space occurring below the equalizer valve and above the standing valve. Liquid ports 70 are formed longitudinally through the liquid control valve housing 55 to establish communication between the chamber 71 and the flow passageway 72.

Mounted within the flow tube 17 at a point above the liquid control valve and the equalizer valve is a fluid control valve. This comprises a control valve housing 73 having an enlarged portion 74 which fits within the flow tube 17 and a reduced downwardly extending tubular portion 75 which extends down into the flow passageway 72. Liquid ports 76 extend through the enlarged portion 74 of the housing 73 and establish communication between the flow passageway 72 and the unrestricted upper length of flow tube.

The upper end of the housing 73 is formed with a central cylindrical bore 77 which terminates in a shoulder 78. A restricted bore 79 continues downwardly through the portion 75 of the housing. The shoulder 78 is formed with a tapered valve seat 80 adjacent to which a spacing bushing 81 is positioned. Resting upon the upper edge of this spacing bushing is an upper valve sleeve 82 formed with a tapered valve seat 83. A central opening 84 through the valve seat 83 has been designed to determine the pressure area for a movable valve plunger 85. This valve plunger is cylindrical, having an upper portion fitting within the valve sleeve 82 and a lower portion fitting within the bore 79 of the housing extension 75. The upper end of the movable valve plunger is formed with a tapered face 86 which rests against the valve seat 83 in the upper valve sleeve 82. Attention is directed to the fact that the end face of the plunger 85 is exposed to pressure exerted through the opening 84 in the valve sleeve 82. Threaded into the upper end of the bore 77 of the valve housing 73 is a plug 87 which has a cavity in its under face to form a chamber 88. Fluid inlet ports 89 extend radially through the side wall of the plug 87 and through the body portion of the valve housing 73. These ports also pass through openings in the flow tube 17 to establish communication between the chamber 88 and the pressure fluid passageway 90. This passageway occurs between the flow tube 17 and the casing 14.

Formed through the side wall of the valve sleeve 82 and communicating with the liquid ports 76 in the housing 73 are pressure fluid outlet ports 91. These ports are effectively closed

when the movable valve plunger 85 is in its uppermost position. The lower end of the valve sleeve 82 is provided with a tapered seat 92 spaced from the tapered seat 80 within the housing extension 75. Occurring between these seats is an enlarged cylindrical portion 93 formed on the circumference of the plunger 85 and a point intermediate its length. The opposite shoulders of this enlarged portion are tapered, as indicated at 94 and 95, and will alternately seat against the faces 92 and 80, respectively, as the plunger reciprocates. A central passageway 96 extends upwardly within the plunger 85 but is closed at its upper end. This passageway lightens the weight of the plunger 85 and also provides a fluid space therein.

A spring 97 is positioned within the lower end of the bore 79 and is held against the lower face of the plunger 85 by a tubular nut 98. The nut 98 is threaded into the bore 79 and fluid is free to pass through it. The lower end of the bore 79 is closed by a plug 99. An exhaust valve 100 is mounted within the plug 99 and will permit flow of fluid outwardly from the bore but will prevent the flow of fluid inwardly thereto.

In operation of the present invention the structure is shown assembled and installed, as indicated particularly in Fig. 1. It will be understood that the casing 14 is set in the well with the well strainer 15 disposed in the productive formation. The flow tube 17 is then lowered into the well and its packer 20 is suitably set to create a passageway 90 for fluid under pressure above the packer and around the flow tube 17, and a passageway 21 below the packer and around the flow tube. By this arrangement fluid under pressure may be delivered from the pipe 19 through the valve 11 and the pipe 13 to the casing. Also by this arrangement the cognate fluid yielded by the geological formation within which the well screen 15 is set will flow into the space 21 beneath the packer and can only flow upwardly through the standing valve 19 and through the flow tube 17, as controlled by the liquid control valve 22 and the fluid control valve, generally indicated at 101 and shown in detail in Fig. 2 of the drawings. The liquid from the formation will then enter the well casing through the well screen 15, and as it fills the space 21 beneath the packer will lift the valve ball 19' in the standing valve 19 and will enter the chamber 102. At this time the valve spool 29 will be in its lowermost position, and the plunger 47 will be in its lowermost position. The liquid will then pass upwardly through the ports 69 and into the chamber 24 and then around the equalizing valve element 30 and through the valve seat 27. It will then pass upwardly into the chamber 71 and will rise through the liquid ports 70 and into the flow passageway 72, after which it will rise in the passageway 72 until it encounters the valve housing 73 of the fluid control valve. The liquid will then pass upwardly through the liquid ports 76 and into the flow tube 17. It is assumed that there is not sufficient pressure in the well to elevate this column of liquid to the top of the well and to cause it to discharge from the upper end of the flow tube 17. It is, therefore, necessary to provide the intermitter structure 12. This is so regulated with relation to the yield of the geological formation as to be actuated when the liquid to be pumped has accumulated a predetermined column within the flow tube 17. Prior to this time the column of liquid accumulated within the flow

tube 17 and down into the chamber 71 will be sufficient to overcome the resistance offered by the valve plunger 47 and its spring 63 to move the valve plunger 47 upwardly, and to at the same time seat the valve elements 30 and 31 on the spool 29. When the valve element 30 is forced against its seat 27 the upward flow of liquid will be interrupted and the desired quantity, as represented by the height of the liquid column, will be entrapped within the structure preparatory to being elevated by the pressure of gas supplied from the pipe 10 through the intermitter valve 11. This is accomplished when the intermitter 12 opens the valve 11 and causes a charge of gas to be forced downwardly within the casing and around the tube 17. Its downward path will be interrupted by the packer 20 and the gas will be diverted through the gas inlet ports 89 and into the chamber 88 in the top of the fluid control valve 101. This pressure will then be sufficient to act upon the surface area of the end of the plunger 85 and force the plunger downwardly so that its tapered end face 86 to overcome pressure of spring 97 will move to an unseated position with relation to the tapered face 83. The gas will then flow through the opening 84 and through the ports 91 into the liquid ports 76, where it will be delivered beneath the column of liquid accumulated within the flow tube 17 and will elevate and discharge this accumulated liquid as a slug from the top of the well. The intermitter 12 is set to close the valve 11 after the slug has been forced from the well. After the valve 11 is closed the gas escapes through the flow pipe until the pressure acting upon the surface area of the end of the plunger 85 is less than the pressure of the spring 97. When this condition is established the spring 97 forces the face 86 of the plunger back against the seat 83 and interrupts the flow of gas into the flow tube 17. At this time it will be evident that the flow of gas has exhausted the accumulated head of liquid within the flow tube, and thus the valve spring 63 of the liquid control valve 22 will force the plunger 47 downwardly and will force the valve element 30 away from its seat 27. Attention is directed to the fact that since there is equal pressure on the opposite sides of the valve element 30 and 31 that the valve spool 29 will be maintained in equilibrium under balanced pressure, and that the valve will move readily to and from its desired position. By this arrangement any amount of liquid available as a yield from a well may be pumped, and the pressure required to actuate the structure will always be the same since the liquid control valve will allow only a certain amount of liquid to enter the tubing at each cycle of its operation. It is to be understood that the joint use of liquid control valve 22 and the fluid control valve 101 is desirable in order to control operation in the event the liquid head should create a pressure greater than that of the operating fluid. The valves might serve useful purposes when used separately, as for example in connection with the structures as shown in my above mentioned co-pending applications, Serial No. 203,451 and Serial No. 203,452, now Patents 2,259,949, October 21, 1941, and 2,251,323, August 5, 1941, respectively.

In further explanation of the valve operation it is to be pointed out that the fluid passageways 48 and 65 within the valve structure shown in Fig. 3 of the drawings form an enclosed chamber which is maintained at substantially atmos-

pheric pressure. The plunger 47 within which chamber 48 is formed is movable and is held downwardly in its closed position by spring 63. When well fluid rises within the tubing 17 it will exert a pressure on the portion of the plunger 47 which is exposed through the opening 68 in the member 52. At this time the equalizing valve element 30 will be submerged within the rising well fluid. When the valve elements 30 and 31 are in their normal opened position as shown in Fig. 3 the liquid pressure is exerted on all sides of the valve elements within chambers 24 and 71 and within the chamber enclosing the nut 36. The pressure acting against the portion of the plunger 47 exposed through the opening 68 is equal to the fluid head times the entire area of the opening 68 the same as if the member 33 were removed. When the well fluid reaches a height at which the pressure exerted against the end of the plunger 47 is sufficient to overcome the resistance of spring 63 the plunger 47 is forced from its seat at 54' and an additional area of the end of the plunger is exposed. This causes the plunger to be forced upwardly within the member 52 in a rapid movement which compresses the spring 63 and lifts the valve elements 30 and 31 so that they will be forced against their seats 27 and 28 to interrupt the inflow of well fluid. The pressure of the well fluid from within the well is then exerted against the bottom of the valve element 30 and against the top of the valve element 31, these elements being of equal area. The passageways 34 and 45 will allow the pressures to remain equal in chamber 71 and in the chamber containing the nut 36. Due to this equal pressure the valve can be opened and closed without effort. When the plunger 47 is seated it seals the chamber 65 at 54' and seals it at 60 when open. It is evident that some leakage will occur while the plunger 47 is moved from open to closed position. This liquid will accumulate in the bottom of the passageway 48 above the exhaust valve 40. As this liquid accumulates the air in chamber 65 and passageway 48 will be compressed and a pressure will be created which will exert a force on the top of the plunger 47 and within the passageway 48 to open the exhaust valve until the pressure within the passageway 48 and that within the chamber 71 are equal. When this pressure reaches a point higher than the pressure in chamber 71 which will be at the lowest point in the pumping cycle liquid will be forced out through the exhaust valve 40 and through the passageway 45 into the chamber 71. If it were not for the system of thus exhausting the fluid which leaks into passageway 48 the valve would become fluid locked and would not function.

With particular reference to Fig. 2 of the drawings, it will be seen that the movable valve element acts normally to close the ports 91 and to prevent communication between the flow pipe 17 and the gas inlet chamber 88. It will also be evident that due to the arrangement of ports 91 in a plane transversely of the movable valve element 85 and at a point below the lower end thereof the pressure exerted by a column of liquid standing in the flow pipe 17 will have no effect upon the movable valve element 85 to move it from its upper and seated position. It will further be noted that the column of liquid will not afford frictional resistance to the movement of the element save as such surface resistance is created by the pressure of the liquid against the

cylindrical side walls of the element in the area of the ports 91. When gas is introduced into the chamber 88 the movable valve element 85 will be acted upon through the bore 84 at the upper end of the sleeve 82. At the instant the valve element 85 is moved downwardly it will be evident that a greater end surface area of the valve element will be uncovered, tending to increase the pressure action on the valve, snapping it against its opposite seat. As the valve moves downwardly it will compress the spring 97, and tapered end faces will rest on seat 80 sealing the chamber around the outside of the plunger when the valve is open. Fluid may have leaked around the movable valve element as it 15 was opened and closed and thus created an accumulated pressure. In any event it will be seen that the pressure of the fluid within the valve housing and within the cavity of the movable valve element will represent the lowest pressure existing in the flow tube and on the outside of the check valve 100 at any point in the cycle of operation of the pumping apparatus.

It will thus be seen that by the construction and arrangement here shown it is possible to 25 completely control and pump a well within which a large or small flow of liquid accumulates as the well flows, and that by the liquid regulating means here disclosed it is possible to discharge the same weight of liquid at each pumping impulse as initiated by the intermitter valve and produced by the gas controlled thereby.

While I have shown the preferred form of my invention as now known to me, it will be understood that various changes may be made in combination, construction and arrangement of parts by those skilled in the art, without departing from the spirit of my invention as claimed.

Having thus described my invention, what I claim and desire to secure by Letters Patent is:

1. In a fluid lift pump mechanism, means for delivering a pressure fluid thereto intermittently a flow tube, an automatic pressure fluid valve comprising a movable valve element and a valve housing fitting within the flow tube of a well fitted with ports through which pressure fluid may pass when the valve is opened and having unobstructed fluid passageways therethrough, a liquid control valve structure below the housing and within the flow tube through which a normally unobstructed flow of liquid may pass, said structure being formed with a valve seat, a balanced valve within said structure and normally unseated, a valve operating structure mounted within the liquid valve housing and being acted upon by the pressure of an accumulated column of liquid passing up through the liquid passageways of said housing and into the flow tube, whereby when a predetermined pressure of liquid has accumulated within the tube the liquid control valve will close and the valve operating means will move the balanced valve within the valve housing to its closed position, a cylindrical bore formed within the housing of the valve structure and within which a movable element connected with the balanced valve reciprocates, and a bypass duct from the cylindrical bore to a point above the balanced valve structure whereby the fluid pressure within the cylindrical bore and the flow tube may be balanced.

2. In a fluid lift pump mechanism, means for delivering a pressure fluid thereto intermittently a flow tube, an automatic pressure fluid valve comprising a movable valve element and a valve housing fitting within the flow tube of a well

fitted with ports through which pressure fluid may pass when the valve is opened and having unobstructed fluid passageways therethrough, a liquid control valve structure below the housing and within the flow tube through which a normally unobstructed flow of liquid may pass, said structure being formed with a valve seat, a balanced valve within said structure and normally unseated, a valve operating structure mounted 10 within the liquid valve housing and being acted upon by the pressure of an accumulated column of liquid passing up through the liquid passageways of said housing and into the flow tube, whereby when a predetermined pressure of liquid has accumulated within the tube the liquid control valve will close and the valve operating means will move the balanced valve within the valve housing to its closed position, a cylindrical bore formed within the housing of the valve structure and within which a movable element connected with the balanced valve reciprocates, a bypass duct from the cylindrical bore to a point above the balanced valve structure whereby the fluid pressure within the cylindrical bore and the flow tube may be balanced, and a valve seat at the top of the cylindrical bore for sealing the cylindrical bore when the passage through the valve structure is closed.

3. In a fluid lift pump mechanism, means for delivering a pressure fluid thereto intermittently a flow tube, an automatic pressure fluid valve comprising a movable valve element and a valve housing fitting within the flow tube of a well fitted with ports through which pressure fluid may pass when the valve is opened and having unobstructed fluid passageways therethrough, a liquid control valve structure below the housing and within the flow tube through which a normally unobstructed flow of liquid may pass, said structure being formed with a valve seat, a balanced valve within said structure and normally unseated, a valve operating structure mounted within the liquid valve housing and being acted upon by the pressure of an accumulated column of liquid passing up through the liquid passageways of said housing and into the flow tube, whereby when a predetermined pressure of liquid has accumulated within the tube the liquid control valve will close and the valve operating means will move the balanced valve within the valve housing to its closed position, a cylindrical bore formed within the housing of the valve structure and within which a movable element connected with the balanced valve reciprocates, a bypass duct from the cylindrical bore to a point above the balanced valve structure whereby the fluid pressure within the cylindrical bore and the flow tube may be balanced, a valve seat at the top of the cylindrical bore for sealing the cylindrical bore when the passage through the valve structure is closed, and a yieldable mounting for the valves within the valve structure with relation to the operating means.

4. In combination with a flow tube of a fluid lift pump, a liquid control valve housing mounted within the flow tube and having liquid passageways therethrough, an equalizer valve housing mounted within the tube below the first named valve housing and spaced therefrom to form a liquid chamber in communication with said passageways, a valve seat within the equalizer valve housing and having a face downwardly presented, a valve element within the equalizer valve housing and normally spaced from said seat, said equalizer valve housing being formed with

ports whereby a free flow of liquid may pass upwardly through the flow tube from beneath the equalizer valve housing through the valve housing into the chamber thereabove and then upwardly through the liquid control valve housing to the flow tube, a cylindrical bore formed within the liquid control valve housing and being closed at its upper end, a tubular valve plunger reciprocating within said bore and being open at its upper end to the space at the closed end of the bore, a valve seat at the lower end of said bore, spring means within the bore tending to force the valve plunger downwardly onto the seat, the seat having an opening therethrough whereby fluid pressure from the chamber beneath the liquid control valve housing may act against the end of the plunger to lift the same in opposition to the action of the spring and connecting means between said plunger and the equalizer valve whereby when the liquid pressure overcomes the strength of the spring the valve plunger will lift and the equalizing valve will be seated, thereby entrapping an accumulated column of liquid within the flow tube having sufficient pressure to lift the plunger, and a fluid passageway to equalize the fluid pressure on opposite sides of the equalizer valve.

5. In combination with a flow tube of a fluid lift pump, a liquid control valve housing mounted within the flow tube and having liquid passageways therethrough, an equalizer valve housing mounted within the tube below the first named valve housing and spaced therefrom to form a liquid chamber in communication with said passageways, a valve seat within the equalizer valve housing and having a face downwardly presented, a valve element within the equalizer valve housing and normally spaced from said seat, said equalizer valve housing being formed with ports whereby a free flow of liquid may pass upwardly through the flow tube from beneath the equalizer valve housing through the valve housing into the chamber thereabove and then upwardly through the liquid control valve housing to the flow tube, a cylindrical bore formed within the liquid control valve housing and being closed at its upper end, a tubular valve plunger reciprocating within said bore and being open at its upper end to the space at the closed end of the bore, a valve seat at the lower end of said bore, spring means within the bore tending to force the valve plunger downwardly onto the seat, the seat having an opening therethrough whereby fluid pressure from the chamber beneath the liquid control valve housing may act against the end of the plunger to lift the same in opposition to the action of the spring and connecting means between said plunger and the equalizer valve whereby when the liquid pressure overcomes the strength of the spring the valve plunger will lift and the equalizing valve will be seated, thereby entrapping an accumulated column of liquid within the flow tube having sufficient pressure to lift the plunger, the tubular plunger being open at its opposite end to the enclosed space within the bore of the liquid control valve housing and being provided with a check valve at its lower end whereby an excess amount of liquid which has leaked by the plunger and into the chamber of the housing will exhaust through the check valve.

6. In a device of the character described, a fluid flow tube within which a column of liquid stands during operation of the device, a fluid control valve mounted within the tube and sub-

stantially beneath the column of liquid, said control valve comprising a tubular housing longitudinally aligned with the tube and being closed at its opposite ends, a fluid chamber at one end of said housing in direct communication with a source of fluid under pressure, an end wall in said chamber formed with a valve seat having a central opening therethrough, a valve element within the housing movable longitudinally and adapted to seat against the valve seat to normally close the opening therethrough, yieldable means for normally holding said movable valve element in its seated position, said housing being formed with gas outlet ports extending laterally through the walls thereof, the outer ends being in free communication with the flow tube, the inner ends being normally closed by said movable valve element and placed in communication with the fluid chamber when the valve element is moved by the fluid to its open position, and means for creating a seal between the valve element and its housing when the valve element is in its seated position and when it is unseated.

7. In a device of the character described, a fluid flow tube within which a column of liquid stands during operation of the device, a fluid control valve mounted within the tube and substantially beneath the column of liquid, said control valve comprising a tubular housing longitudinally aligned with the tube and being closed at its opposite ends, a fluid chamber at one end of said housing in direct communication with a source of fluid under pressure, an end wall in said chamber formed with a valve seat having a central opening therethrough, a valve element within the housing movable longitudinally and adapted to seat against the valve seat to normally close the opening therethrough, yieldable means for normally holding said movable valve element in its seated position, said housing being formed with gas outlet ports extending laterally through the walls thereof, the outer ends being in free communication with the flow tube, the inner ends being normally closed by said movable valve element and placed in communication with the fluid chamber when the valve element is moved by the fluid to its open position, and means for creating a seal between the valve element and its housing when the valve element is in its seated position and when it is unseated.

8. In a device of the character described, a flow tube within which a column of liquid may stand and from which it is elevated, a valve housing mounted within said tube adjacent the lower end thereof and enveloped by the liquid in said column, said housing being closed at its opposite ends, a pressure fluid chamber in the upper end of said housing, a valve chamber within the housing below said first named chamber and in communication therewith through a valve opening lying in a horizontal plane, ports extending horizontally through the side wall of the housing and establishing communication between the valve chamber and the flow tube within which the column of liquid may stand, a movable valve element within the valve chamber normally closing the ports in communication with the tube and the passageway between the fluid pressure chamber and the valve chamber whereby the pressure exerted by the column of liquid will act against the sides of the valve element and pres-

sure exerted by the pressure fluid within the pressure chamber to act against the end of the valve element to move the same, means for introducing fluid under pressure to the pressure chamber, and yieldable means for acting upon the valve element to normally hold it in its seated position.

9. In a device of the character described, a flow tube within which a column of liquid may stand and from which it is elevated, a valve housing mounted within said tube adjacent the lower end thereof and enveloped by the liquid in said column, said housing being closed at its opposite ends, a pressure fluid chamber in the upper end of said housing, a valve chamber within the housing below said first named chamber and in communication therewith through a valve opening lying in a horizontal plane, ports extending horizontally through the side wall of the housing and establishing communication between the valve chamber and the flow tube within.

5 which the column of liquid may stand, a movable valve element within the valve chamber normally closing the ports in communication with the tube and the passageway between the fluid pressure chamber and the valve chamber whereby the pressure exerted by the column of liquid will act against the sides of the valve element and pressure exerted by the pressure fluid within the pressure chamber to act against the end of the valve element to move the same, means for introducing fluid under pressure to the pressure chamber, yieldable means for acting upon the valve element to normally hold it in its seated position, means permitting fluid within the valve chamber to equalize in pressure with the lowest pressure of the fluid within which the valve structure is submerged, and means for closing the valve after the slug has been forced from the well because of a reduction in pressure 10 around the valve.
